Primary Examiner — Samantha Q Lawrence*Assistant Examiner* — Thanh Luu Wong(74) *Attorney, Agent, or Firm* — Jeff B. Vockrodt;
Culhane Meadows PLLC(57) **CLAIM**

The ornamental design for a dermal spray apparatus, as shown and described.

DESCRIPTION

FIG. 1 is an enlarged partial perspective view of top, front, and right sides of a dermal spray apparatus showing our new design;

FIG. 2 is an enlarged perspective view showing top, front, and left sides thereof;

FIG. 3 is a front elevation view thereof, showing the dermal spray apparatus in a closed position;

FIG. 4 is a back elevation view thereof, showing the dermal spray apparatus in a closed position;

FIG. 5 is a left-side elevation view thereof;

FIG. 6 is a right-side elevation view thereof;

FIG. 7 is a top plan view thereof; and,

FIG. 8 is a bottom plan view thereof.

The broken lines depict portions of the dermal spray apparatus that form no part of the claim.

1 Claim, 8 Drawing Sheets(56)
